UNLOADING SYSTEM FOR VOLATILE LIQUIDS

Emory D. Mattix and Charles W. Stokes, Lake Charles, La., assignors to Cities Service Refining Corporation, Lake Charles, La., a corporation of Delaware

Application December 3, 1949, Serial No. 131,016

8 Claims. (Cl. 103—37)

1

This invention relates to pumping systems, and more particularly to a system for transferring volatile liquids such as propane and butane from tank cars to storage.

In transferring volatile liquids such as propane and butanes from tank cars to bulk storage, one or more cars are usually manifolded to a single delivery line, and natural gas under pressure is admitted to the cars in order to force the liquid to storage. When a large number of cars are manifolded to the system, the gas pressure may be insufficient to force the liquid through at the desired rate, and for this reason it is desirable to interpose a pump in the line to aid in the delivery of the liquid to storage. It is necessary at all times to maintain an adequate head of liquid on the pump inlet to prevent damage to the equipment.

Due to variations in pressures in the various cars, and also due to variations in the opening of the valves of the cars, there is always a tendency for one of the cars to run dry before the remainder are empty. Gas may then enter the delivery line and pump, lowering the head of liquid in the pump, and in extreme cases, gas may be forced into the storage tanks. When this occurs, the entire operation must be shut down in order to bleed the gas from the pump, storage tanks, and delivery lines.

Tank cars designed for transporting propane and butanes are usually provided with excess flow valves in conjunction with their discharge valves to limit the flow of liquid through the valve to a maximum value. When this maximum flow is exceeded, the valves close, and cannot be re-opened until the gas pressure on the interior of the car has been balanced with the pressure in the car outlet line. Manual setting of the discharge valve cannot be accurately judged. For this reason it is customary to set the discharge valves so that a gallonage per minute substantially below the limit of the excess flow valve is withdrawn from the car. It follows that the time required to unload the car is far longer than the time which would be necessary if liquid were being withdrawn at the maximum rate allowed by the excess flow valves.

An undesired closure of an excess flow valve may also cause other difficulties in operation. Thus, if the pump were to continue to pull as much liquid as before, it would have a tendency to pull additional liquid from the other cars manifolded to the system, with consequent overloading and progressive closing of the other excess flow valves. This results in a condition in which the pressure in the inlet line to the pump drops sharply, with consequent vaporization of liquid, and gassing in the pump and inlet lines.

2

It is an object of this invention to provide an unloading system for volatile liquids operative to bleed automatically excess vapors from the system, to maintain withdrawal of liquid from the cars during moderate gassing conditions, and to control automatically the rate of withdrawal of liquid from the cars to avoid closure of the excess flow valves, to insure the most rapid possible unloading of the cars.

10 The operation of our improved unloading system will be described more particularly in connection with the accompanying drawing in which

Fig. 1 is a diagrammatic showing of an unloading system embodying our invention, and

15 Fig. 2 illustrates a detail of a tank car unloading mechanism.

In the operation of our system a number of tank cars are drawn up on a siding and the collection lines 5 of the cars are connected to the collection lines 10 of our system. The cars will normally be provided with hand valves 6, and with excess flow valves 7 which are normally biased in open position by means of spring 8. A gas injection line 9 is provided in order to maintain pressure on the inside of the car during unloading operations. Liquid from the cars is drawn through collecting lines 10 and pump inlet line 11 to a pump 12, which is preferably of a well type in order to insure that there is sufficient head of liquid on the pump mechanism at all times. If the cars are placed on an elevated trestle, so that the normal head of liquid in line 11 is sufficient to maintain at all times a sufficient head of liquid on the pump, then any other type of pump may be used. The pump has an outer wall 13 defining a well chamber, and is provided with an inner wall 14 defining a flow passage 15. The liquid in the pump will flow from the well through the flow passage 15 and through pump outlet line 16 to storage. The pump 12 is provided with an impeller 17 located within the flow passage 15 and driven by shaft 18 which is driven by any suitable source of power, the source illustrated in the drawing being a steam turbine 19 having a steam inlet line 20 and a steam outlet line 21.

The outlet line 16 is provided with a flow controller 25, which may be any standard control but which is preferably of the rotameter type since this type of control is operative over wider flow ranges than other meter controls. The flow controller is operative to vary the air pressure in line 28 in response to variations in flow in outlet line 16 to first control a throttle valve 26 normally biased in closed position in the outlet line 16, and also a valve 27 also normally biased in closed position in the steam inlet line 20, air supply be-

ing obtained from air supply line 27. Valves 26 and 27 are split ranged in such a manner that valve 26 will be fully opened at air pressures in line 28 below that at which the valve 27 will begin to open.

After the desired number of tank cars are connected to the collection lines 10, natural gas will be admitted under a pressure of say 60 p. s. i. through the pressure line 9 and the hand control valve 6 will be opened to allow passage of liquid from the tank cars to the pump. At the same time the flow controller 25 will be set so as to limit the passage of liquid through the outlet line 16 to an amount slightly less than that limited by the total capacity of the excess flow valves of cars manifoldeled to the system. Thus if the excess flow valves 7 are of a type which will allow passage of say 50 gallons per minute before closing, and there are five cars manifoldeled to the system, the flow controller 25 will be so set as to control the flow of liquid through outlet line 16 to a maximum of slightly less than 250 gallons per minute.

If only one car is manifoldeled to the system, the pressure of the natural gas, combined with the vapor pressure of the liquid in the tank car, will, except in very cold weather or in the event of low natural gas pressure, probably be sufficient to force the amount limited by the excess flow valve of the car to storage without the necessity of using the pump. The flow controller 25 would be set to pass a given amount, say 49 gallons per minute, through the outlet line 16. Under these assumed conditions the flow controller would operate to control the pressure in the air control line 28 to open valve 26 to the degree necessary to pass the desired amount of liquid. If this amount is less than that which the valve 26 can pass when it is fully opened, the air pressure will be so controlled in line 28 as to open valve 26 only to the degree necessary.

If more cars are manifoldeled to the system and the pressure within the tank cars is insufficient to overcome friction in the system and to force the desired quantity of liquid through the line 16 when the valve 26 is wide-open, it will be necessary to operate the pump 12. In this case the flow controller 25 would be so set that sufficient air pressure would be maintained in the air control line 28 to open the valve 26 to its fullest extent and also to open valve 30 in the steam line 20 to the desired degree. For example, the control on valve 26 may be so set that at pressures, determined by the setting of the flow controller 25, below 3 p. s. i. in the control line 28 the valve 26 would remain closed; at a pressure of say 9 p. s. i., valve 26 would be fully open, and at intermediate pressures the valve 26 would be open to a lesser degree depending upon the pressure. Valve 27 would be so adjusted that at pressures in control line 28 below nine pounds the valve would remain closed, but at pressures above nine pounds the valve would begin to open, being fully opened at a pressure of 15 pounds. The 15 pounds pressure in line 28 would normally be found only when the maximum number of tank cars are manifoldeled to the system; however, in very cold weather, or in case of a failure of pressure in the natural gas input to the cars it is possible that the valve 27 would be opened to its fullest degree when less than the maximum number of cars are manifoldeled.

Thus by means of these controls it is possible to accurately limit the withdrawal of fluids from the tank cars to the amount fixed by the maxi-

mum capacity of the excess flow valves of the tank cars, avoiding any closure of the valves during operation, and yet allowing the maximum gallonage to be pulled from the tank cars, insuring a rapid and even unloading thereof.

The controls described above are sufficient to attain the objects of our invention under normal conditions, while there still remains liquid to be withdrawn in all of the tank cars. In the event that for one reason or another one of the tank cars should run dry before the others, natural gas will be forced into the system and will accumulate in the well of the pump 12. In order to insure a continuous evacuation of this gas from the float chamber until the hand valve 6 of the dry car has been closed to cut off flow of gas into the system, another set of controls is provided. Thus the pump 12 has attached thereto float chamber 32 connected by upper and lower connection lines 33 and 34. The float chamber contains a float 35, connected with valve control means 36 responsive to changes in the liquid level in the float chamber, and operative to control the air pressure in air control line 40 to operate a valve 37 normally biased in closed position in a flare gas line 38 leading from the float chamber 32, and a valve 40 normally biased in open position in the steam inlet line 20, air being supplied from air supply line 41. In the event that gas from an empty car should enter the well of the pump 12, thereby causing the liquid level within the well to drop to a point below that indicated by the dotted lines in the pump well, the valve control means 36 will first operate to open flare gas valve 37 to evacuate the gas accumulation to a degree which will maintain the liquid level in the pump 12 at the indicated height, to permit continuous pumping from the cars which are not yet empty. If the flow of gas into the pump is greater than the flow which can be handled by the flare gas line valve 37, the liquid level in the float chamber will continue to drop. In this event, the valve control means 36 will operate to increase the air pressure in the control lines 39 and cause the valve 40 to throttle the turbine 19 so that the rate of pumping will be lowered.

Thus under normal circumstances valve 37 might be so set as to remain closed at air pressures in control line 39 until at nine pounds pressure it is opened to its fullest extent. At pressures above nine pounds valve 40 will begin to close, throttling completely at fifteen pounds pressure. Thus by the operation of the controls it is possible to insure that the pump is never in operation when there is an inadequate supply of liquid within the pump well.

As pointed out above vaporization in the system may be due to other causes than one tank car running dry before the others are empty. Thus a closure of an excess flow valve due to improper maintenance or other abnormal condition might cause liquid to be withdrawn from the other tank cars at such a rate that there is a progressive closing of other excess flow valves and the pull of the pump will cause the pressure in the intake line 11 and in the pump well to drop to such an extent that vaporization will take place. In such a case the liquid level controller 36 will operate valve 37 and valve 40 to vent gases from the system and to close down the pump.

It is of note that neither control, alone, is operative to correct conditions which may arise within the system giving cause to vaporization in a manner to assure a minimum unloading time. However, together the controls operate to main-

tain a steady flow of liquid through the pump until all cars have been evacuated.

Our invention provides an automatic remedy for a vexatious problem in the art of handling liquefied petroleum gases. It may be easily installed in any presently existing pumping system, and is quickly responsive to any changes in the conditions prevailing in the system.

Having now disclosed our invention, what is claimed as new and useful is:

1. A pumping system for transferring volatile liquids including in combination a pump, pump inlet and outlet lines, a float chamber connected to the pump, means for varying the output of the pump, a flare gas line leading from the float chamber, a valve in the flare gas line, and a liquid level controller responsive to variations in the liquid level in the float chamber, and operative to control the means for varying the output of the pump and the opening of flare gas line valve to maintain the liquid level in the float chamber at a constant value.

2. A pumping system for transferring volatile liquids including in combination a pump, pump inlet and outlet lines, a float chamber connected to the pump, means for varying the output of the pump, a flare gas line leading from the float chamber, a valve in the flare gas line, and a liquid level controller operative, in the event of excess gas accumulation in the float chamber, to control the means for varying the output of the pump and the opening of the flare gas line valve in a manner to first vary the opening of the flare gas line valve to vent excess gas, while maintaining the pump output at a constant rate, and second, in the event of excess gas accumulation in the float chamber at a rate greater than can be vented through the flare gas line to lessen the output of the pump.

3. A pumping system for transferring volatile liquids including in combination a pump, a pump inlet line and outlet line, flow control means in the outlet line, a second means for varying the output from the pump, a flow controller responsive to variations in flow through the outlet line operative to control both the flow control means in the outlet line and the second means for limiting the output of the pump to maintain a constant flow of liquid through the outlet line when the system is operating under nongassing conditions, a float chamber connected to the pump, a third means for varying the output of the pump, a flare gas line leading from the float chamber, and a liquid level controller responsive to variations of the liquid level in the float chamber and operative to control the third means for varying the output of the pump and the opening of the flare gas line valve to maintain the liquid level in the float chamber at a constant value.

4. The pumping system according to claim 3 in which the liquid level controller is operative, in the event of excess gas accumulation in the float chamber, to first vary the opening of the flare gas line valve to vent excess gas, while maintaining the pump output at a constant rate, and second, in the event of excess gas accumulation in the float chamber at a rate greater than can be vented through the flare gas line, to lessen the output of the pump.

5. A pumping system for transferring volatile liquids including in combination a pump, pump inlet line, and pump outlet lines, a float chamber connected to the pump, a flare gas line leading from the float chamber, a valve in the flare gas

line, means for varying the speed of the pump, and a liquid level controller responsive to variations of the liquid level in the float chamber operative to vary the opening of the flare gas line valve and the speed of the pump in response to variations in the liquid level in the float chamber whereby to maintain said liquid level at a constant value.

6. A pumping system for transferring volatile liquids including in combination a pump, pump inlet line and outlet line, a float chamber connected to the pump, a flare gas line leading from the float chamber, a valve in the flare gas line, means for varying the speed of the pump, and a liquid level controller responsive to variations of the liquid level in the float chamber operative, in the event of a lowering of the liquid level in the float chamber, to first open the flare gas line valve, and, in the event of a continued lowering of the liquid level in the float chamber, to reduce the speed of the pump, whereby to cause the said liquid level to return to its normal height.

7. A pumping system for transferring volatile liquids including in combination a pump, means for varying the speed of the pump, pump inlet and outlet lines, a valve and a flow meter in the pump outlet line, a float chamber connected to the pump, a flare gas line connected to the float chamber, a valve in the flare gas line, a flow controller sensitive to variations in flow through the pump outlet line operative to vary the opening of the outlet line valve and the speed of the pump, and a liquid level controller responsive to variations of the liquid level in the float chamber operative to vary the opening of the flare gas line valve and the speed of the pump in response to variations in the liquid level in the float chamber due to gassing conditions in the pump, whereby to cause the said liquid level to return to its normal height.

8. A pumping system for transferring volatile liquids including in combination a pump, means for varying the speed of the pump, pump inlet and outlet lines, a valve and a flow meter in the outlet line, a float chamber connected to the pump, a flare gas line connected to the float chamber, a valve in the flare gas line, a flow controller sensitive to variations in flow through the pump outlet line operative to vary the opening of the outlet line valve and the speed of the pump to maintain a constant flow of liquid through the outlet line under nongassing conditions, and a liquid level controller responsive to variations of the liquid level in the float chamber operative, in the event of a lowering of the liquid level in the float chamber due to gassing conditions in the pump, to first open the flare gas line valve and, in the event of a continued lowering of the liquid level in the float chamber, to reduce the speed of the pump whereby to cause the said liquid level to return to its normal height.
